UNITED STATES PATENT OFFICE

JOSEPH GHISLERI, OF VINCENNES, FRANCE

SORDINO FOR REED MUSICAL INSTRUMENTS

Application filed June 23, 1927, Serial No. 200,976, and in France April 25, 1927.

The present invention relates to a movable and adjustable sordino for saxophones and clarinettes, and in general for all reed musical instruments.

5 The sordino is adapted to regulate the muffling of the sounds in reed musical instruments by means of a device which may be mounted on the tube for the admission of air to the instrument and on the upper part of 10 the tube.

The sordino essentially comprises a cylindrical body which as regards its transversal cross section consists of suitable blades separated by air spaces in alternate disposition, 15 and is pierced at its centre with a circular aperture through which is inserted the body or shank of a bolt or shaft whose head has the same transversal cross-section as the cylindrical body and which can be held against 20 the said body by means of a nut or knob. Due to the adjustment of the position of the said bolt head, the blades and spaces of the cylinder and the head can be placed in the proper relative position, and the device can thus be 25 mounted at the air inlet of the instrument in order to produce a greater or less muffling effect.

The appended drawings show by way of example an embodiment of the invention. 30 Fig. 1 is an elevational view of the sordino. Fig. 2 is a bottom plan view of the same. Fig. 3 is an elevational view of the bolt, with the nut or knob removed. Fig. 4 is a plan view of the bolt head with 35 sections of elastic packing material secured thereto.

Fig. 5 is an elevational view of the cylinder, Fig. 6 the corresponding plan view. Fig. 7 shows the sordino mounted on a 40 clarinet and Fig. 8 shows it mounted upon a saxophone. Having more particular reference to the drawings wherein like characters of reference will designate corresponding parts throughout, the numeral 1 indicates a substantially cylindrical body made of metal or other suitable materials. As regards its transversal cross section, it consists of the blades 8 and of spaces which are in alternate disposition 45 and in suitable number. It is pierced at its

centre with a circular aperture 2 through which is inserted the body or shank 4 of the bolt which is shown in Fig. 3 and whose head 3, which has the same transversal cross section as the body 1, consists of the blades 8^a 55 and alternating spaces. The body 4 of the bolt carries a thread 5 by which the usual nut, milled head, wing nut or the like 6 may hold the body 1 against the head 3 of the bolt.

The blades 8^a of the bolt head 3 are preferably shorter than the blades 8 of the cylindrical body 1, and have glued or otherwise secured to their outer surface 7, sections of resilient material 7 such as cork, india rubber, or the like, adapted through frictional 60 engagement to properly hold the device in position on the musical instrument.

The operation is as follows:

Before the nut 6 is screwed down, I suitably dispose the spaces and the blades 8^a of the head of the bolt and the corresponding parts of the cylinder in a relative position such that the device which is situated at the air inlet of the instrument can produce a greater or less muffling effect. 70

Figs. 7 and 8 show by way of example the arrangement of the sordino device respectively upon a clarinette and a saxophone.

In Fig. 7, which represents the device mounted upon a clarinette, the sordino 1 is 80 secured in the lower portion of the mouthpiece 11 by means of the sections of the resilient material 7 on the bolt head 3, and the device is adjusted from the bottom by the nut 6 and before placing the mouthpiece 11 upon 85 the air inlet tube 10 of the instrument.

In Fig. 8, which shows my improved device used in connection with a saxophone, the sordino 1 is secured to the air inlet tube 15 of the instrument by means of the sections of resilient material 7 secured to the bolt head 3, and the device is adjusted from the top by the nut 6. The mouthpiece 16 is then placed upon the tube 15. 90

Manifestly, the construction shown and described is capable of many modifications without changing the nature of the invention.

I may for instance modify the details of construction and assembling according to cir- 100

cumstances and to the utilization of the apparatus.

The several parts of the apparatus may be replaced by others having the same function and affording like results.

It is obvious that I may utilize all suitable substances or products which are suitable for the manufacture of such sordinoes.

I claim:

10. 1. A sordino of the character described comprising a substantially cylindrical body presenting in transversal cross-section a plurality of spaced blades and means cooperatively associated with said body and being
15 adjustable with respect to the body to open or close the spaces between the blades of said body dependent upon the muffling effect to be produced.
20. 2. A sordino of the character described comprising a substantially cylindrical body presenting in transversal cross-section a plurality of spaced blades and a bolt head cooperatively associated with said body and having the same formation as the body, said
25 bolt head being adjustable with respect to said body for opening or closing the spaces between the blades of the latter dependent upon the muffling effect to be produced.
30. 3. A sordino of the character described comprising a substantially cylindrical body presenting in transversal cross-section a plurality of spaced blades and having a bore throughout its longitudinal central portion, a bolt freely received and retained within
35 said bore in the body and a head rigid with said bolt and being adjustable with respect to said body for opening or closing the spaces between the blades of the latter.
40. 4. A sordino of the character described comprising a substantially cylindrical body presenting in transversal cross-section a plurality of spaced blades and having a bore throughout its longitudinal central portion, a bolt freely received within said bore and
45 extending beyond the body, a head rigid with one end of the bolt said head having the same formation as the body and a knob secured to the free end of the bolt adapted to move said head into adjustment with respect to the
50 body.
55. 5. A sordino for reed musical instruments comprising a body removably received within the air inlet portion of the instrument said body presenting in transversal cross-section a plurality of spaced blades, a head carried by and adjustable with respect to said body for opening or closing the spaces between blades of the latter and resilient means secured to the head whereby the sordino is held
60 in position in said air inlet portion of the instrument.

In testimony whereof he has affixed his signature.
